2,479,994

MACHINE FOR SETTING UP CELLULAR CARTONS

James E. Annen, Kalamazoo, Mich., assignor to Sutherland Paper Company, Kalamazoo, Mich.

Application October 31, 1945, Serial No. 625,842

30 Claims. (Cl. 93—37)

1

This invention relates to improvements in machine for setting up cellular cartons.

The main objects of this invention are:

First, to provide a machine for setting up cellular cartons which are designed to be manufactured for distribution in the flat or collapsed condition and set up to receive the contents.

Second, to provide a machine of this character which is comparatively simple in structure and of very large capacity.

Third, to provide a cellular carton setting up machine which is not likely to become clogged in use and is fully automatic in operation.

Objects relating to details and economies of the invention will definitely appear from the description to follow. The invention is defined in the claims.

A machine which embodies the features of the invention is clearly illustrated in the accompanying drawing, in which:

Figure 1 is a plan view of a carton setting up machine embodying the invention, a set of cartons being shown in completely set up position and as discharged from the setting up mechanism.

Fig. 2 is an enlarged fragmentary view partially in vertical section on line 2—2 of Figs. 1 and 4, a plurality of cartons being illustrated in the hopper. Certain movements are indicated by dotted lines and certain of the parts are shown at an intermediate stage of operation.

Fig. 3 is a side elevation view from the right of Fig. 1, certain parts being partially broken away.

Fig. 4 is a fragmentary view partially in vertical transverse section on lines corresponding to lines 4—4 of Figs. 1, 2 and 3.

Fig. 5 is an enlarged fragmentary view partially in vertical section on line 5—5 of Fig. 1 illustrating certain details of the carton discharge mechanism.

Figs. 6, 7 and 8 are enlarged fragmentary views in vertical section on a line corresponding to line 6—6 of Fig. 9 showing different stages of movement of the parts in bringing the carton to fully erected position.

Fig. 9 is an enlarged fragmentary view partially in section on line 9—9 of Fig. 8 showing further details of the erecting mechanism and with the parts in the relative position shown in Fig. 8.

Fig. 10 is a fragmentary view of the parts shown in Fig. 9 in which the cell partitions are in fully erected position.

Fig. 11 is an enlarged fragmentary view partially in longitudinal section illustrating the initial step in setting up a carton.

2

I have illustrated the invention as I have embodied it in a machine designed to set up cartons, designated generally by the numeral 1, which are manufactured for distribution and storage in collapsed form as shown for example in Fig. 2 of the drawings. Generally stated, these cartons comprise outwardly diverging side walls 2 and 3, longitudinal partition 4, and outwardly inclined bottom members 5 extending from the lower edges of the side walls and the partitions, being formed integrally therewith. The transverse partitions 6 are hingedly connected to the side walls and when erected are adapted to extend transversely between the same with their lower ends extending through slots 7 in the bottom. The cover 8 extends from one of the side walls. This somewhat general description of the carton is given as it is believed it will facilitate the understanding of the invention as disclosed herein.

The cartons are arranged in a hopper or magazine 9 which is of trough-like section and adapted to receive the collapsed cartons, supporting them in an upright position. The side walls 10 of the hopper are provided with inwardly projecting stops 11 which coact with the inwardly projecting stops 12 on the brackets 13 in supporting the stack of cartons while permitting them to be withdrawn one by one, the end edges of the cartons snapping past these stops when they are gripped by the suction cups 14 of the feeding arms 15 which are mounted on the tubular rockshaft 16 connected to a suitable source of vacuum as the pump 17, conventionally shown in Fig. 3, the connection being shown at 18 and the control valve for the connection at 19. A tappet valve 20 is provided to cooperate with the arm 15 to shut off the vacuum after the carton has been delivered to the table to be picked up by the feed slide 28.

The transfer or feed arms 16 are actuated in timed relation to the actuation of certain other parts by means of the cam 21 acting upon the connecting rod 22 which is connected to the arm 23 on the rockshaft. This feed or transfer means delivers the cartons one by one to the table 24, preferably inclined as illustrated. This insures the contacting of the cartons with the table as they are advanced thereon. As the cartons are swung downwardly upon the table they are engaged by the studs or fingers 25 on the table, these fingers passing through certain of the slots 7 in the lower bottom member 5 of the carton, that is, lower with respect to the table, 55 and the carton is partially opened as shown in

Fig. 11 to be engaged by the feed slides or members 26 slideable in the slideways 27.

The slides 26 are reciprocated in their ways by the rocker arms 28 on the rockshaft 29, the rocker arms being made up of telescoping sections 30 and 31; the sections 30 are secured to the rockshaft 29 while the sections 31 are secured to the slides. The rockshaft is actuated from the main drive shaft 32 which is provided with a cam member 33 connected by the link 34 to the arm 35 on the rockshaft 29 (Fig. 3). The drive shaft 32 is driven by a chain 321 through a reduction gear 322 by the motor 323.

The cartons are advanced by the slides to the position shown in Fig. 2 with the extended cover 8 engaging the stop 36. With the cartons in this position they are engaged by the erector arms 37, there being three such arms in the embodiment illustrated. These erector arms 37 are mounted on the common rockshaft 38, the table being provided with slots or elongated openings 39 through which they swing into engagement with the carton positioned as shown in Fig. 2; the carton is engaged and the walls and bottom members swung to erected position as shown in Figs. 6 and 7. Certain of the successive steps are illustrated in these figures. The rockshaft 38 is provided with a crank arm 381 having a cam follower 382 thereon coacting with the cam 383 on the periphery of the cam member 33. The faces 40 of the erector arms 37 are designed to perform certain functions or steps in the erection of the cartons. These faces are provided with V-shaped notches 41 which engage the trailing edges of the cartons as they are delivered by the slides 26, the slides being notched at 42 to engage the trailing edges of the cartons as in the partially open position shown in Fig. 11.

Supported in opposed relation to the erector arms is a spreader abutment 43 having a curved face 44. As the erectors apply pressure to the trailing edge of the carton the upper edge of the front wall of the carton, or the upper wall as appears in Figs. 5 and 7, is forced against the curved face of the abutment 43 and slides upwardly along the same until it engages the overhanging fingers 45 which serve the purpose of stops and prevent the distortion of the walls of the cartons. The fingers are provided with downturned ends 46 which further prevent deforming of the cartons as they are opened or erected.

When the erector arms reach the position shown by dotted lines in Fig. 6 the continued thrust on the trailing edge swings the bottom members 5 of the carton downwardly on to the rearwardly diverging supporting surfaces 47 which extend from the V notches 41. The erector members are provided with fingers 48 at their outer ends which coact with the outer surfaces 47 to provide V recesses 49, similar V recesses 50 being provided to receive the bottom edges of the inner walls of the carton. This prevents the carton from slipping out of place and it is completely extended and supported to permit the erection of the cross or transverse partitions. The abutment member is provided with a series of longitudinal recesses 44 which receives the top edge of the longitudinal partition 4 of the carton.

While the carton is supported with its walls fully erected as shown in Fig. 7 the cross head 51 carrying a series of partial erector fingers 52 is actuated, there being two rows of these fingers corresponding to the two rows of cells. These

fingers reciprocate through holes 53 in the forming head 43, see Figs. 7 and 8. The cross head 51 is mounted on the supports 54 for compound movement, that is, a lateral or front to rear movement to project and retract the fingers and also a longitudinal movement to impart a final erecting movement to the transverse partitions and snap them into the openings in the bottom members. It will be noted that the fingers 52 have nose portions 55 which engage the transverse partitions as the fingers are projected and the cross head is shifted longitudinally, see Figs. 9 and 10. In Fig. 10 the fingers have been projected to the limit of their forward stroke and the partitions swung to substantially erected position.

The longitudinal movement of the cross head 51 indicated by dotted lines in Fig. 9 forces the partitions to the position shown in Fig. 10, in which position their lower ends snap through the openings 7 in the bottom members of the carton. In the embodiment illustrated the cross head is provided with rearwardly projecting arms 56 to which the actuating lever 57 is connected by means of the cross rod 58. This lever is pivoted at 59 and is actuated by the link 60 having a follower 61 coacting with a cam 62. The cross head is shifted longitudinally by means of the lever 63 which is pivoted at 64 and provided with a follower 65 coacting with the cam 66. The swinging end of the lever engages the slot 67 in the cross head. These cams are mounted on the shaft 32 so that the parts are actuated in timed sequence.

When the cartons have been fully erected they are engaged by the transfer slide 68 reciprocatingly mounted on the rod 69 supported at one side of the erecting table and at the top of the delivery chutes 70 (Fig. 1). The cartons are delivered by the transfer slide to the chutes 70 which are provided with converging guides 71. As the cartons are delivered to these chutes they are engaged for positive feed by the pushers 72 which are carried by the rod 73 which is in turn carried by the brackets 74 and 75 pivoted at 76, see Figs. 1 and 5. The operating link 77 is connected to the arm 78 on the rockshaft 46. The link 79 connects the cross bar 80 to the pusher slides 81 having a second pusher 82 mounted thereon so that the cartons are successively engaged and pushed into a semi-nesting relation on the table or chute 83; that is, they are nested to the extent that one carton overlies the extended cover of the preceding carton. The cartons may be removed from the table 83 for filling.

The transfer slide 68 is actuated in timed relation to the other mechanisms through the arm 85 on the rockshaft 86, the arm comprising telescoping sections 87 and 88 (Fig. 5). As the carton is shifted by the transfer slide it engages the stop 89 (Fig. 5) thereby allowing further movement of the transfer slide and disengaging it from the carton. The transfer slide is provided with a spring gripping finger 90. The rockshaft 86 is provided with arm 91 actuated by the link 92 provided with cam followers 93 and 94 coacting with the cams 95 and 96, respectively (Fig. 4). The operation is entirely automatic. The cartons are placed in the magazine 9 in upright position and are advanced to feeding position by means of the roller 97.

I have illustrated and described the invention in a very practical embodiment thereof. I have not attempted to illustrate or describe further 75 modifications and adaptations which I contem-

plate as it is believed this disclosure will enable the adaptation of the invention as may be desired.

Having thus described my invention what I claim as new and desire to secure by Letters Patent is:

1. In a machine of the class described, the combination of a forwardly inclined magazine adapted to receive a stack of collapsed cellular cartons with their covers disposed upwardly, a rearwardly inclined table provided with a longitudinal way and having a plurality of transversely aligned holes adjacent its front end and a plurality of transversely aligned longitudinal slots disposed rearwardly of said holes, stops releasably engaging the ends of the first of the stack of cartons, transfer means comprising a tubular rockshaft having a plurality of angled suction arms reciprocating through said holes and provided with suction cups adapted to engage the forward carton of the stack and transfer the same to the table as the arms are retracted, means for cutting off the vacuum when the arms are in retracted position, pins on said table acting to partially open the cartons as they are delivered to the table by said suction cup transfer means, a feed slide coacting with said way and engaging the rear edge of a partially opened carton, a stop coacting with the front edge of the cover of a carton delivered by said slide, a plurality of erector arms pivotally mounted below said table to swing upwardly through said slots therein into engagement with the rear edge of a carton delivered by said slide while its cover is in engagement with said stop, said erector arms being provided with V-shaped notches engaging the rear edge of the partially opened carton and with V-shaped recesses at each side of said notches, surfaces of which supportingly engage the bottom members of the opened carton, a rearwardly facing carton wall spreader abutment having a curved face disposed in opposed relation to said erector arms as they are actuated, said abutment having a central longitudinal groove adapted to receive the longitudinal partition of a carton and having overhanging carton retaining fingers at the top of its curved face, said abutment having a series of holes therein corresponding to the cells of the carton, and a cross head provided with a series of partition erecting fingers reciprocable in said holes in said abutment member and having laterally projecting nose portions, said cross head being mounted and actuated for reciprocating and lateral movement whereby the fingers are first projected into the carton to partially erect transverse partition members thereof and moved longitudinally of the carton to complete the erection of the partition members.

2. In a machine of the class described, the combination of a table provided with a longitudinal way and having a plurality of transversely aligned longitudinal slots, a feed slide coacting with said way and engaging the rear edge of a partially opened carton, a stop coacting with the front edge of the cover of a carton delivered by said slide, a plurality of erector arms pivotally mounted below said table to swing upwardly through said slots therein into engagement with the rear edge of a carton delivered by said slide while its cover is in engagement with said stop, said erector arms being provided with V-shaped notches engaging the rear edge of the partially opened carton and with V-shaped recesses at

each side of said notches, surfaces of which supportingly engage the bottom members of the opened carton, a rearwardly facing carton wall spreader abutment having a curved face disposed in opposed relation to said erector arms as they are actuated, said abutment having a central longitudinal groove adapted to receive the longitudinal partition of a carton and having overhanging carton retaining fingers at the top of its curved face, said abutment having a series of holes therein corresponding to the cells of the carton, and a cross head provided with a series of partition erecting fingers reciprocable in said holes in said abutment member and having laterally projecting nose portions, said cross head being mounted and actuated for reciprocating and lateral movement whereby the fingers are first projected into the carton to partially erect transverse partition members thereof and moved longitudinally of the carton to complete the erection of the partition members.

3. In a machine of the class described, the combination of a forwardly inclined magazine adapted to receive a stack of collapsed cellular cartons with their covers disposed upwardly, a rearwardly inclined table provided with a longitudinal way and having a plurality of transversely aligned holes adjacent its front end and a plurality of transversely aligned longitudinal slots disposed rearwardly of said holes, stops releasably engaging the ends of the first of the stack of cartons, transfer means comprising a tubular rockshaft having a plurality of angled suction arms reciprocating through said holes and provided with suction cups adapted to engage the forward carton of the stack and transfer the same to the table as the arms are retracted, means for cutting off the vacuum when the arms are in retracted position, pins on said table acting to partially open the cartons as they are delivered to the table by said suction cup transfer means, a feed slide coacting with said way and engaging the rear edge of a partially opened carton, a stop coacting with the front edge of the cover of a carton delivered by said slide, a plurality of erector arms pivotally mounted below said table to swing upwardly through said slots therein into engagement with the rear edge of a carton delivered by said slide while its cover is in engagement with said stop, said erector arms being provided with V-shaped notches engaging the rear edge of the partially opened carton and with V-shaped recesses at each side of said notches, surfaces of which supportingly engage the bottom members of the opened carton, a rearwardly facing carton wall spreader abutment disposed in opposed relation to said erector arms as they are actuated, said abutment having a series of holes therein corresponding to the cells of the carton, and a cross head provided with a series of partition erecting fingers reciprocable in said holes in said abutment member.

4. A machine of the class described, the combination of a table provided with a longitudinal way and having a plurality of transversely aligned longitudinal slots, a feed slide coacting with said way and engaging the rear edge of a partially opened carton, a stop coacting with the front edge of the cover of a carton delivered by said slide, a plurality of erector arms pivotally mounted below said table to swing upwardly through said slots therein into engagement with the rear edge of a carton delivered by said slide while its cover is in engagement with said stop, said erector arms

being provided with V-shaped notches engaging the rear edge of the partially opened carton and with V-shaped recesses at each side of said notches, surfaces of which supportingly engage the bottom members of the opened carton, a rearwardly facing carton wall spreader abutment disposed in opposed relation to said erector arms as they are actuated, said abutment having a series of holes therein corresponding to the cells of the carton, and a cross head provided with a series of partition erecting fingers reciprocable in said holes in said abutment member.

5. In a machine of the class described, the combination of a forwardly inclined magazine adapted to receive a stack of collapsed cellular cartons with their covers disposed upwardly, a rearwardly inclined table provided with a longitudinal way and having a plurality of transversely aligned holes adjacent its front end and a plurality of transversely aligned longitudinal slots disposed rearwardly of said holes, stops releasably engaging the ends of the first of the stack of cartons, transfer means comprising a tubular rock-shaft having a plurality of angled suction arms reciprocating through said holes and provided with suction cups adapted to engage the forward carton of the stack and transfer the same to the table as the arms are retracted, means for cutting off the vacuum when the arms are in retracted position, pins on said table acting to partially open the cartons as they are delivered to the table by said suction cup transfer means, a feed slide coacting with said way and engaging the rear edge of a partially opened carton, a stop coacting with the front edge of the cover of a carton delivered by said slide, an erector arm swingable through said table into engagement with the rear edge of a carton delivered by said slide while its cover is in engagement with said stop, said arm being provided with a notch engaging the rear edge of a partially opened carton and with recesses at each side of the notch having oppositely inclined surfaces extending from the edges of the notch for supportingly engaging the bottom members of an opened carton, a wall spreading abutment member disposed in opposed relation to said erector as it is actuated, and means for erecting the transverse partitions of a carton while the carton is supported between said erector and abutment.

6. In a machine of the class described, the combination of a forwardly inclined magazine adapted to receive a stack of collapsed cellular cartons with their covers disposed upwardly, a rearwardly inclined table provided with a longitudinal way and having a plurality of transversely aligned holes adjacent its front end and a plurality of transversely aligned longitudinal slots disposed rearwardly of said holes, stops releasably engaging the ends of the first of the stack of cartons, transfer means comprising a tubular rockshaft having a plurality of angled suction arms reciprocating through said holes and provided with suction cups adapted to engage the forward carton of the stack and transfer the same to the table as the arms are retracted, means for cutting off the vacuum when the arms are in retracted position, pins on said table acting to partially open the cartons as they are delivered to the table by said suction cup transfer means, a feed slide coacting with said way and engaging the rear edge of a partially opened carton, a stop coacting with the front edge of the cover of a carton delivered by said slide, and means for fully erecting the walls of the carton while so supported.

7. In a machine of the class described, the combination of a table, means for partially opening cartons and delivering the same in such partially opened condition to said table and with their covers extending forwardly, a feed slide engaging the rear edge of a partially opened carton, a stop coacting with the front edge of the cover of a carton delivered by said slide, a plurality of erector arms pivotally mounted below said table to swing upwardly therethrough into engagement with the rear edge of a carton delivered by said slide while its cover is in engagement with said stop, said erector arms being provided with notches engaging the rear edge of the partially opened carton and with recesses at each side of said notches, a rearwardly facing carton wall abutment having a curved face disposed in opposed relation to said erector arms as they are actuated, said abutment having a central longitudinal groove adapted to receive the longitudinal partition of a carton, said abutment having a series of holes therein corresponding to the cells of the carton, and a cross head provided with a series of partition erecting fingers reciprocable in said holes in said abutment member and having laterally projecting nose portions, said cross head being mounted and actuated for reciprocating and lateral movement whereby the fingers are first projected into the carton to partially erect transverse partition members thereof and moved longitudinally of the carton to complete the erection of the partition members.

8. In a machine of the class described, the combination of a table, means for partially opening cartons and delivering the same in such partially opened condition to said table and with their covers extending forwardly, a feed slide engaging the rear edge of a partially opened carton, a stop coacting with the front edge of the cover of a carton delivered by said slide, a plurality of erector arms pivotally mounted below said table to swing upwardly therethrough into engagement with the rear edge of a carton delivered by said slide while its cover is in engagement with said stop, said erector arms being provided with notches engaging the rear edge of the partially opened carton and with recesses at each side of said notches, a rearwardly facing carton wall abutment having a curved face disposed in opposed relation to said erector arms as they are actuated, said abutment having a series of holes therein corresponding to the cells of the carton, and a cross head provided with a series of partition erecting fingers reciprocable in said holes in said abutment member.

9. In a machine of the class described, the combination of a table provided with a carton stop, means for positioning a carton in said table in partially open position with its cover engaged with said stop, a plurality of erector arms pivotally mounted below said table to swing upwardly therethrough into engagement with the rear edge of a carton disposed with its cover in engagement with said stop, said erector arms being provided with V-shaped notches engaging the rear edge of the partially opened carton and with V-shaped recesses at each side of said notches, surfaces of which supportingly engage the bottom members of the opened carton, a rearwardly facing carton wall spreader abutment having a curved face disposed in opposed relation to said erector arms as they are actuated, said abutment having a central longitudinal groove adapted to receive the longitudinal partition of a carton and having overhanging carton retaining fingers at the

top of its curved face, said abutment having a series of holes therein corresponding to the cells of the carton, and a cross head provided with a series of partition erecting fingers reciprocable in said holes in said abutment member and having laterally projecting nose portions, said cross head being mounted and actuated for reciprocating and lateral movement whereby the fingers are first projected into the carton to partially erect transverse partition members thereof and moved longitudinally of the carton to complete the erection of the partition members.

10. In a machine of the class described, the combination of a table provided with a carton stop, means for positioning a carton in said table in partially open position with its cover engaged w'th said stop, a plurality of erector arms pivotally mounted below said table to swing upwardly therethrough into engagement with the rear edge of a carton disposed with its cover in engagement with said stop, said erector arms being provided with notches engaging the rear edge of the partially opened carton and with recesses at each side of said notches, surfaces of which supportingly engage the bottom members of the opened carton, a rearwardly facing carton wall spreader abutment disposed in opposed relation to said erector arms as they are actuated, said abutment having a series of holes therein corresponding to the cells of the carton, and a cross head provided with a series of partition erecting fingers reciprocable in said holes in said abutment member and having laterally projecting nose portions, said cross head being mounted and actuated for reciprocating and lateral movement whereby the fingers are first projected into the carton to partially erect transverse partition members thereof and moved longitudinally of the carton to complete the erection of the partition members.

11. In a machine of the class described, the combination of a table provided with a carton stop, means for positioning a carton in said table in partially open position with its cover engaged with said stop, a plurality of erector arms pivotally mounted below said table to swing upwardly therethrough into engagement with the rear edge of a carton disposed with its cover in engagement with said stop, said erector arms being provided with notches disposed for engaging the rear edge centrally of the bottom of the partially opened carton and with shaped recesses at each side of said notches disposed for receiving therein the bottom members of the carton on the opposite sides of said rear edge, and a rearwardly facing carton wall spreader abutment fixed relative to said erector arms and having a curved face disposed in opposed relation to said erector arms as they are actuated, said abutment having a central longitudinal groove adapted to receive the longitudinal partition of a carton, said abutment being spaced from said table to permit the cover to lie between the abutment and table when the cover engages said stop.

12. In a machine of the class described, the combination of a table provided with a carton stop, means for positioning a carton in said table in partially open position with its cover engaged with said stop, a plurality of erector arms pivotally mounted below said table to swing upwardly therethrough into engagement with the rear edge of a carton disposed with its cover in engagement with said stop, said erector arms being provided with notches disposed for engaging the rear edge centrally of the bottom of the partially opened carton and with recesses at each side of said

notches disposed for receiving therein the bottom members of the carton on the opposite sides of said rear edge, and a rearwardly facing carton wall spreader abutment fixed relative to said erector arms and disposed in opposed relation to said erector arms as they are actuated, said abutment being spaced from said table to permit the cover to lie between the abutment and table when the cover engages said stop.

13. In a machine of the class described, the combination of a table slidably supporting cartons, means for delivering a carton to said table and partially opening it as it is delivered to the table, means for translating the partially opened carton on said table, a forwardly swinging erector adapted to engage the trailing edge of a carton in its partially open position, an abutment opposed to said erector and adapted to receive the thrust of the carton while acted upon by said erector, and a cross head disposed at the rear of the abutment and provided with a series of partition erecting fingers adapted to erect the transverse partitions while the carton is supported by said erector and abutment.

14. In a machine of the class described, the combination of a table, a stop coacting with the front edge of the cover of a carton disposed on said table, an erector mounted below said table to swing upwardly therethrough into engagement

30 with the rear edge of a carton while its cover is in engagement with said stop, said erector being provided with a notch engaging the rear edge of the carton and with recesses at each side of said notch receiving the bottom members of the erected carton, a rearwardly facing carton wall abutment having a curved face disposed in opposed relation to said erector arm as it is actuated, said abutment having a central longitudinal groove adapted to receive the longitudinal partition of a carton and having a series of holes therein, and a cross head provided with a series of partition erecting fingers longitudinally and laterally reciprocable in said holes in said abutment member and having laterally projecting nose portions.

45 15. In a machine of the class described, the combination of a table, a stop coacting with the front edge of the cover of a carton disposed on said table, an erector mounted below said table to swing upwardly therethrough into engagement

50 with the rear edge of a carton while its cover is in engagement with said stop, said erector being provided with a notch engaging the rear edge of the carton and with recesses at each side of said notch receiving the bottom members of the erected carton, a rearwardly facing carton wall abutment disposed in opposed relation to said erector arm as it is actuated and provided with erecting finger receiving holes, and a cross head provided with a series of partition erecting fingers

55 60 longitudinally and laterally reciprocable in said holes in said abutment member and having laterally projecting nose portions.

65 16. In a machine of the class described, the combination of a table, a stop coacting with the front edge of the cover of a carton disposed on said table, an erector mounted below said table to swing upwardly therethrough into engagement with the rear edge of a carton while its cover is in engagement with said stop, said erector being provided with a notch disposed for engaging the rear edge centrally of the bottom of the carton and with recesses at each side of said notch receiving the bottom members of the erected carton on the opposite sides of said rear edge, and a

70 75 rearwardly facing carton wall abutment fixed

relative to said erector and disposed in opposed relation to said erector as it is actuated, said abutment being spaced from said table to permit the cover to lie between the abutment and table when the cover engages said stop.

17. In a machine of the class described, the combination of a table, an erector arm pivotally mounted below said table to swing upwardly therethrough into engagement with the rear edge of a carton on said table, a rearwardly facing carton wall spreader abutment having a curved face disposed in opposed relation to said erector as it is actuated, said abutment having a central longitudinal groove adapted to receive the longitudinal partition of a carton and having overhanging carton retaining fingers at the top of its curved face, said abutment having a series of holes therein corresponding to the cells of the carton, and a cross head provided with a series of partition erecting fingers reciprocable in said holes in said abutment member and having laterally projecting nose portions, said cross head being mounted and actuated for reciprocating and lateral movement whereby the fingers are first projected into the carton to partially erect transverse partition members thereof and moved longitudinally of the carton to complete the erection of the partition members.

18. In a machine of the class described, the combination of a table, an erector arm pivotally mounted below said table to swing upwardly therethrough into engagement with the rear edge of a carton on said table, a rearwardly facing carton wall spreader abutment having a curved face disposed in opposed relation to said erector as it is actuated, said abutment having a series of holes therein corresponding to the cells of the carton, and a cross head provided with a series of partition erecting fingers reciprocable in said holes in said abutment member.

19. In a machine of the class described, the combination of a table, means for positioning a partially open carton thereon, an erector arm swingable through said table into engagement with the rear edge of a carton, said arm being provided with a notch engaging the rear edge of a partially open carton and with recesses at each side of the notch having oppositely inclined surfaces extending from the edges of the notch for supportingly engaging the bottom members of an opened carton, a wall spreading abutment member disposed in opposed relation to said erector as it is actuated, said notch being disposed relative to said oppositely inclined surfaces to engage said rear edge of said partially opened carton and to further open said carton prior to said supporting engagement of said inclined surfaces with said bottom walls as said erector is actuated toward said abutment and means for erecting the transverse partitions of a carton while the carton is supported between said erector and abutment.

20. In a machine of the class described, the combination of a table, means for partially opening a carton, and delivering the same in such partially opened condition to said table and with its cover extending forwardly, means for translating the partially opened carton on said table, a forwardly swinging erector adapted to engage the trailing edge of a carton in its partially opened position, said erector being provided with a notch engaging the trailing edge of the partially opened carton and with recesses at each side thereof

receiving and supporting the bottom portion of the carton with its wall in extended position, and an abutment disposed in coacting opposed relation to the erector, said abutment having a curved face and a central longitudinal groove adapted to receive the longitudinal partition of a carton and having a series of holes therein corresponding to the cells of the carton, and a cross head provided with a series of partition erecting fingers reciprocable in said holes in said abutment member, said cross head being mounted and actuated for reciprocating and lateral movement whereby the fingers are first projected into the carton to partially erect transverse partition members thereof and moved longitudinally of the carton to complete the erection of the partition members.

21. In a machine of the class described, the combination of a table, means for partially opening a carton, and delivering the same in such partially opened condition to said table, and with its cover extending forwardly, means for translating the partially opened carton on said table, a forwardly swinging erector adapted to engage the trailing edge of a carton in its partially opened position, said erector being provided with a notch engaging the trailing edge of the partially opened carton and with recesses at each side thereof receiving and supporting the bottom portion of the carton with its wall in extended position, and an abutment disposed in coacting opposed relation to the erector and having a series of holes therein corresponding to the cells of the carton, and a cross head provided with a series of partition erecting fingers reciprocable in said holes in said abutment member.

22. In a machine of the class described, the combination of a table, means for partially opening a carton, and delivering the same in such partially opened condition to said table and with its cover extending forwardly, means for translating the partially opened carton on said table, a forwardly swinging erector adapted to engage the trailing edge of a carton in its partially opened position, an abutment disposed in coacting opposed relation to the erector, and a cross head provided with a series of partition erecting fingers, said cross head being mounted and actuated for reciprocating and lateral movement whereby the fingers are first projected into the carton to partially erect transverse partition members thereof and moved longitudinally of the carton to complete the erection of the partition members.

23. In a machine of the class described, the combination of a table adapted to translatable support collapsed cartons with their covers extending forwardly, an erector engaging the rear edge of a partially erected carton for imparting forward thrust thereto and conformed to receive and support the bottom of an erected carton, a rearwardly facing abutment disposed in opposed relation to the erector to receive the thrust of the upper wall of a carton as it is moved to erected position, a cross head provided with a plurality of partition erecting fingers projectable through said abutment into engagement with the lateral partitions of a carton for swinging them into erected position, a discharge member adapted to shift the erected cartons endwise when released by the erector, a guideway for supporting and guiding said discharge member for movement substantially on a level with said table at one side of the same and in a direction transverse the path of movement of the erector in erecting the

cartons, and means for moving said discharge member along said guideway for discharging the erected cartons.

24. In a machine of the class described, the combination of a table adapted to translatablely support collapsed cartons with their covers extending forwardly, an erector engaging the rear edge of a partially erected carton for imparting forward thrust thereto and conformed to receive and support the bottom of an erected carton, a rearwardly facing abutment disposed in opposed relation to the erector to receive the thrust of the upper wall of a carton as it is moved to erected position, a discharge member adapted to shift the erected cartons endwise when released by the erector, a guideway for supporting and guiding said discharge member for movement substantially on a level with said table at one side of the same and in a direction transverse the path of movement of the erector in erecting the cartons, and means for moving said discharge member along said guideway for discharging the erected cartons.

25. In a machine of the class described, the combination of a table adapted to translatablely support collapsed cartons with their covers extending forwardly, an erector engaging the rear edge of a carton for imparting forward thrust thereto and conformed to support the bottom of an erected carton, a rearwardly facing abutment disposed in opposed relation to the erector to receive the thrust of the carton as it is acted upon by said erector, a plurality of partition erecting fingers adapted to be projected into engagement with the lateral partitions of a carton while the carton is supported by said erector and abutment, a discharge member adapted to shift the erected cartons endwise when released by the erector, a guideway for supporting and guiding said discharge member for movement substantially on a level with said table at one side of the same and in a direction transverse the path of movement of the erector in erecting the cartons, and means for moving said discharge member along said guideway for discharging the erected cartons.

26. In a machine of the class described, the combination of a table slidably supporting cartons, means for delivering a carton to said table and partially opening it as it is delivered to the table, said means for partially opening the cartons including fingers projecting upwardly from the table for engaging the cartons as the same are moved towards the table, means for translating the partially opened carton on said table, an erector adapted to engage the trailing edge of a carton in its partially open position, an abutment opposed to said erector and adapted to receive the thrust of the carton while acted upon by said erector, a cross head disposed at the rear of the abutment and provided with a series of partition erecting fingers adapted to erect the transverse partitions while the carton is supported by said erector and abutment.

27. In a machine of the class described, the combination of a table, an erector adapted to engage the trailing edge of a carton in its partially open position, an abutment opposed to said erector and adapted to receive the thrust of the carton while acted upon by said erector, a cross head disposed at the rear of the abutment and provided with a series of partition erecting fingers adapted to erect the transverse partitions while the carton is supported by said erector and abutment, said fingers being fixedly connected to said

cross head to move as a unit therewith and means for moving said cross head both longitudinally and transversely of itself.

28. In a machine of the class described, the combination of an erecting table for slidably supporting cartons, an erector adapted to engage the trailing edge of a carton, an abutment opposed to said erector and adapted to receive the thrust of the carton while acted upon by said erector, a cross head disposed at the rear of the abutment and provided with a series of partition erecting fingers adapted to erect the transverse partitions while the carton is supported by said erector and abutment, a delivery table disposed at the side of said erecting table, a reciprocating discharge member provided with a spring jaw engageable with an end of an erected carton for discharging the same from between said abutment and erector after retraction of the erector, a stop limiting the lateral discharge movement of the carton, continued movement of the discharge member disengaging the jaw from said carton, a chute delivering to said discharge table and to which the cartons are delivered by said discharge member, and a conveyor adapted to engage the cartons as they are successively delivered by said discharge member to said chute and deliver the same to said delivery table in overlapping relation, a guideway for supporting and guiding said spring jaw for movement substantially on a level with said table at one side thereof and in a direction transverse the path of movement of said erector in erecting the cartons, and means for moving said spring jaw along said guideway to discharge the cartons from between said abutment and erector after erection of the same.

29. In a machine of the class described, the combination of an erecting table for slidably supporting cartons, an erector adapted to engage the trailing edge of a carton, an abutment opposed to said erector and adapted to receive the thrust of the carton while acted upon by said erector, a cross head disposed at the rear of the abutment and provided with a series of partition erecting fingers adapted to erect the transverse partitions while the carton is supported by said erector and abutment, a delivery table disposed at the side of said erecting table, a reciprocating discharge member provided with a spring jaw engageable with an end of an erected carton for discharging the same from between said abutment and erector after retraction of the erector, a stop limiting the lateral discharge movement of the carton, continued movement of the discharge member disengaging the jaw from said carton, a chute delivering to said discharge table and to which the cartons are delivered by said discharge member, and a conveyor adapted to engage the cartons as they are successively delivered by said discharge member to said chute and deliver the same to said delivery table in overlapping relation, a guideway for supporting and guiding said spring jaw for movement substantially on a level with said table at one side thereof and in a direction transverse the path of movement of said erector in erecting the cartons, and means for moving said spring jaw along said guideway to discharge the cartons from between said abutment and erector after erection of the same.

30. In a machine of the class described, the combination of an erecting table for slidably supporting cartons, an erector adapted to engage the trailing edge of a carton, an abutment opposed to said erector and adapted to receive the thrust

of the carton while acted upon by said erector, a cross head disposed at the rear of the abutment and provided with a series of partition erecting fingers adapted to erect the transverse partitions while the carton is supported by said erector and abutment, a discharge member for discharging an erected carton from between said erector and abutment after retraction of the erector, and a chute to which the cartons are delivered by said discharge member, a guideway for supporting and guiding said discharge member for movement substantially on a level with said table at one side of the same and in a direction transverse the path of movement of the erector in erecting the cartons, and means for moving said discharge

member along said guideway to discharge the cartons.
